UNITED STATES PATENT OFFICE.

HENRY AIKEN, OF PITTSBURG, PENNSYLVANIA.

BOLSTER.

No. 895,323.

Specification of Letters Patent. Patented Aug. 4, 1908.

Application filed February 19, 1908. Serial No. 416,651.

To all whom it may concern:

Be it known that I, HENRY AIKEN, of Pittsburgh, in the county of Allegheny and State of Pennsylvania, have invented a new and useful Improvement in Bolsters, of which the following is a full, clear, and exact description, reference being had to the accompanying drawings, forming part of this specification, in which—

Figure 1 is a front elevation, partly in section, showing a car provided with my improved bolsters; Figs. 2 and 3 are cross sections on the lines II—II and III—III of Fig. 1, respectively, showing the body bolster; and Figs. 4 and 5 are respectively a longitudinal section of the end portion and a central cross section of the truck bolster.

My invention relates to the class of bolsters, both body bolsters and truck bolsters, and is designed to provide a cheap, simple and strong construction therefor.

To that end, the invention consists in forming the compression member of a steel casting, with its end portions flowed about, and thereby secured to, the wrought metal tension member.

It also consists in providing the spacer and center plate structure at intermediate points, by casting it as part of the compression member, and preferably shaped so as to fit the wrought tension member.

In the drawings, referring to Figs. 1, 2 and 3, 2 represents the cast steel compression member of the body bolster, which may be provided with integral side flanges of any desirable cross sectional shape and having its end portions flowed and cast about the perforated ends of the tension member 3. This tension member is shown as consisting of an inverted channel having side flanges 4, 4, the web being perforated at the ends, as shown in Fig. 2. In this case, I have also shown the end portion of the compression member as formed of skeleton shape, containing cavities 5, for lightness in the part inclosing the channel tension member.

As shown in Fig. 3, the strut or center plate portion 6 is formed as a cast hollow box, with its top portion shaped to fit neatly within the channel and its lower portion having a center plate boss 7, and a guide sleeve 8, to receive the king pin. The compression member with its central spacer or strut and center plate may be formed by any suitable mold which is arranged to receive the compression member, so that the metal may be

cast against it at the central portion and around and inclosing it at the end portions.

Referring now to Fig. 1, in connection with Figs. 4 and 5, 9 is the cast compression member of the truck bolster, having its end portions 10 flowed and cast around the hooked or bent end portions 11 of the rolled or wrought tension member. At the same time that the compression member is cast, I preferably cast integral with it the center plate 12, the spacer block 13 having a recessed lower portion 14, to fit over the tension member and the king pin sleeve 15. These parts may be of any desirable form, and the shape and arrangement of the casting in either case may be widely varied, as well as the shape and connection of the wrought metal member, since I consider myself the first to form a bolster of a cast compression member whose integral ends are flowed about and inclose the end portions of the tension member. In either case, the center plate and spacer block may be formed separately from the compression member.

The advantages of my invention result from the cheapness, simplicity and strength of the structure, the use of rivets, bolts and other fastening means being done away with, a stronger construction being afforded at small labor cost. By flowing steel or other cast metal through or around one of the parts, they are firmly secured together and the end portions of the body bolster may be easily shaped to provide means for securing to the car body, while in the case of the truck bolster, the spring plate may be formed integrally with the casting.

Many changes may be made in the form and arrangement of the parts without departing from my invention.

I claim:

1. A bolster having a wrought metal tension member and a cast metal compression member with its integral end portions flowed about and inclosing the tension member, substantially as described.

2. A bolster having a cast metal compression member with its integral end portions flowed through and around holes or recesses formed in the tension member, substantially as described.

3. A bolster having a cast metal compression member with the ends of the tension member embedded therein, the compression member having an integral center plate structure, substantially as described.

4. A bolster having a cast compression member with a center plate spacer block and king pin socket formed integral therewith, the ends of the compression member being flowed about and inclosing the end portions of the tension member, substantially as described.
5. A bolster having a cast compression member with an integral cast spacing structure arranged to fit against the central por-

tion of the tension member, the ends of the tension member being embedded in the cast metal forming the compression member, substantially as described.

In testimony whereof, I have hereunto set my hand.

HENRY AIKEN.
